STOVE CONSTRUCTION

Herbert M. Reeves, Kankakee, Ill., assignor to
 Florence Stove Company, Gardner, Mass., a
 corporation of Massachusetts

Application August 27, 1948, Serial No. 46,405

3 Claims. (Cl. 126—39)

1

The invention concerns improvements in the construction of cookstoves, and more particularly to cookstoves of the type in which the stove body is made up of a chassis and panels fabricated from sheet metal.

One object of the invention is to simplify the assembly of the end panels with the chassis and provide for removal and replacement of the panels without requiring disconnection of the stove or its movement away from the wall or other structure against which it is installed.

Another object is to provide fastening means for securing the end panels to the chassis, which means is very simple in construction, quick and easy acting, and which minimizes the stresses imposed on the panels both in shipment and in use, thereby avoiding damage to the enamel coating of the panels.

Other objects and advantages of the invention will become apparent from the following detailed description of the preferred embodiment illustrated in the accompanying drawing, in which:

Figure 1 is an end elevational view of a cook-stove embodying the features of the invention.

Fig. 2 is a perspective view of the cookstove chassis.

Fig. 3 is a fragmentary sectional view of the chassis and one end panel taken in a vertical plane substantially on the line 3—3 of Fig. 1.

Fig. 4 is a sectional view taken on a horizontal plane substantially on the line 4—4 of Fig. 3.

Fig. 5 is a fragmentary rear view of one of the end panels and the means for securing it to the chassis.

Fig. 6 is a fragmentary sectional view taken in a horizontal plane substantially on the line 6—6 of Fig. 1.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

For purposes of illustration, the invention has been shown as applied to a table-type cookstove having a body 10 (Fig. 1) supported on a base 11 and adapted to be mounted flush against an upright wall 12. The stove body 10 comprises a rigid generally rectangular frame or chassis 13 (Fig. 2) closed at opposite ends by sheet metal

2

end panels 14. The panels 14 as well as other exposed parts of the stove are usually finished with a coating of vitreous enamel.

In the exemplary stove the chassis 13 is constructed largely of sheet metal stampings designed to provide maximum strength and rigidity with minimum weight. As shown in Fig. 2, the chassis 13 comprises a flat rear member 15 and a front member 16 formed with large laterally spaced openings 17 for the oven, broiler and utility compartments of the stove. The front and rear members are connected at opposite ends adjacent their upper edges by elongated end members 18, herein shown as channel-shaped in cross-section. Other end members 19, preferably of Z-shaped cross-section, connect the front and rear members adjacent their lower edges. It will be understood of course that the various members of the chassis are welded or otherwise secured together to form a rigid structure.

In accordance with the invention, the chassis 13 and the end panels 14 are constructed so as to facilitate the assembly of the end panels with and their removal from the chassis, and to minimize the strains imposed on the panels when assembled with the chassis. The panels 14, except for being shaped for right and left-hand mounting, respectively, are alike in construction. As will be seen by reference to Fig. 1 of the drawings, the panels 14 are generally rectangular and each has its upper edge extended as at 18' adjacent the rear edge of the panel to provide a support and end closure for a splasher back 19'. Preferably the panels are made somewhat wider than the front to rear dimensions of the chassis 13 and are mounted so as to project at the rear thereof to define with the rear chassis member 15 and the wall 12, an insulating space for protection of the wall.

As herein shown, each panel 14 comprises a generally rectangular face portion 20 with integral flanges along its four side edges. Thus each panel has a flange 21 at its upper edge, a flange 22 at its front edge, a flange 23 at its rear edge, and a flange 24 at its lower edge. These flanges extend substantially at right angle to the face of the panel, and the flanges 21, 22 and 24 have their marginal edges turned inwardly into a plane spaced from and substantially parallel to the face of the panel.

In addition to stiffening the panel 14, the flanges 21—24 serve as a part of the means for securing the panels to the chassis 13. To this end the chassis is provided at its front corners 55 with anchoring members herein shown as verti-

cally disposed forwardly projecting flanges 25 for cooperation with the flanges 22 of the panels, the flanges 25, in this instance being formed at opposite ends of the front chassis member 16. The end members 18 of the chassis are likewise provided with horizontally disposed upwardly projecting flanges 26 for cooperation with the panel flanges 21. The flanges 26 extend along the upper edges of the end members and are disposed in the same planes as the companion flanges 25 and are thus positioned for engagement with the panel flanges 22 and 23 when the panels are assembled with the chassis.

Cooperating fastening elements are provided on one of the panel flanges and on the chassis for securing each panel to the chassis adjacent its rear edges and for maintaining the front panel and chassis flanges in interlocking engagement. The fastening elements at each end of the stove body include an upwardly projecting hook element 30 carried by an elongated fastening member 31 secured to the end member 18. As herein shown, the member 31 is channel-shaped in cross-section and is spot welded at one end to the end member 18. The hook element 30 is formed as an upstanding lug on the opposite or free end of the fastening member and is spaced rearwardly of the chassis so as to aline with the rear flange 23 of the panel 14 when the latter is assembled with the chassis. The rear end portion of the member 31 is offset outwardly from the member 18 so as to locate the hook element 30 closely adjacent the plane of the chassis flanges 25 and 26. A diagonal brace 32 extending between the free end of the fastening member and a gusset plate 33 anchored in the lower forward corner of the chassis assists in holding the fastening member rigid.

For cooperation with the hook elements 30, each of the panels 14 is provided with a suitable hook-engaging element. As shown in Figs. 3 and 5, the hook-engaging element is formed by offsetting inwardly a section 35 of the rear panel flange 23 and cutting away the lower portion of the section to form a slot 36 positioned to receive the hook.

To facilitate the engagement of the hook element 30 in the slot 36, the element 30 is tapered to a relatively sharp point 37. Preferably this taper is formed by inclining the rear edge 38 of the element as shown in Fig. 5. The inclined edge serves the additional purpose of urging the panel rearwardly and thus establishing a firm locking engagement between the front flange 22 of the panel and the companion flange 25 of the chassis when the panel is assembled therewith.

With the construction above described, an end panel may be assembled with the chassis by simply hooking the front flange 22 over the flange 25 while the panel is held in a slightly elevated position, and then shifting the panel downwardly to engage the upper flange 21 with the flange 26 and the hook element 30 in the slot 36. The limit position of the panel is determined by the flange of the cross-member 19 upon which the lower flange 24 of the panel is adapted to rest, and by engagement of the inwardly turned edge portion of the flange 22 with the upper web of the end member 18. The panel may then be permanently secured to the stove by means of screws or bolts inserted through the member 19 and flange 24 and through the flange 26 and panel flange 21. The last-mentioned screws or bolts are concealed from sight by the cooking or work-

ing top plate 40, which in the final stove assembly is supported on the cross-members 18.

It will be apparent from the foregoing that the invention provides a stove chassis and panel construction of novel and advantageous character. The chassis and the panels embody coacting fastening means of a very simple character, which greatly simplifies the assembly of the parts and which provides an effective vibrationless connection while imposing a minimum of stress upon the panels. Damage to the enamel coating of the panels is thus greatly reduced in the handling of the stoves during shipment or installation.

I claim as my invention:

1. The combination with a stove chassis having generally rectangular front and rear members connected at opposite ends adjacent their upper edges by elongated end members, vertically disposed forwardly projecting flanges at opposite ends of the front member, horizontally disposed upwardly projecting flanges extending along the upper edges of said end members, end panels having inwardly turned flanges along their front and upper edges positioned for cooperative engagement respectively with the vertical and horizontal flanges of said chassis members, a fastening member at each end of the chassis presenting an upwardly projecting hook element, and a member rigid with each panel having a downwardly facing slot positioned to receive the associated hook element as the panel is shifted downwardly to engage the cooperating flanges, said hook element having a tapered nose portion engageable with the slotted member and tending to urge the panel rearwardly of the chassis whereby to firmly lock the cooperating panel and chassis flanges together.

2. The combination with a stove chassis having generally rectangular front and rear members connected at opposite ends adjacent their upper edges by elongated end members, vertically disposed forwardly projecting flanges at opposite ends of the front member, horizontally disposed upwardly projecting flanges extending along the upper edges of said end members, end panels having inwardly turned flanges along their front and upper edges positioned for cooperative engagement respectively with the vertical and horizontal flanges of said chassis members, a fastening member at each end of the chassis presenting an upwardly projecting hook element, a member rigid with each panel having a downwardly facing slot positioned to receive the associated hook element as the panel is shifted downwardly to engage the cooperating flanges, and cross-members extending between the ends of said front and back chassis members adjacent their lower edges defining supports for said panels.

3. The combination with a stove chassis having generally rectangular front and rear members connected at opposite ends adjacent their upper edges by elongated end members, vertically disposed forwardly projecting flanges at opposite ends of the front member, horizontally disposed upwardly projecting flanges extending along the upper edges of said end members, end panels having inwardly turned flanges along their front and upper edges positioned for cooperative engagement respectively with the vertical and horizontal flanges of said chassis members, a fastening member at each end of the chassis presenting an upwardly projecting hook element, a member rigid with each panel having a downwardly facing slot positioned to

receive the associated hook element as the panel is shifted downwardly to engage the cooperating flanges, cross-members extending between the ends of the front and back chassis members adjacent their lower edges, said panels having inturned flanges extending along their lower edges resting on said cross-members, and fasteners rigidly securing the last-mentioned flanges to said cross-members.
